DESIGN FOR A DISPLAY EASEL, FOR CHEWING GUM OR THE LIKE

Karl Fink, Brooklyn, N. Y., assignor to Topps Chewing Gum, Inc., Brooklyn, N. Y., a corporation of New York

Application March 28, 1940, Serial No. 91,294

Term of patent 7 years

To all whom it may concern:

Be it known that I, Karl Fink, a citizen of the United States and a resident of Brooklyn, in the county of Kings and State of New York, have invented a new, original, and ornamental Design for a Display Easel, for Chewing Gum or the like, of which the following is a specification, reference being had to the accompanying drawing, forming a part thereof.

Figure 1 is a front perspective view, on a reduced scale, of a display easel, for chewing gum or the like, showing my design;

Figure 2 is an end elevational view;
Figure 3 is a rear elevational view;

Figure 4 is a top plan view;

Figure 5 is a fragmentary face view; taken in the direction of line 5—5 of Figure 2.

I claim:

The ornamental design for a display easel, for chewing gum or the like, substantially as shown.

KARL FINK.
